THREAD CONTROL FOR WEFT
REPLENISHING LOOMSGeorge N. Peterson, Grafton, Mass., assignor to
Crompton & Knowles Loom Works, Worcester,
Mass., a corporation of Massachusetts

Application February 23, 1949; Serial No. 77,791

5 Claims. (Cl. 139—247)

1

This invention relates to thread controls for weft replenishing looms and it is the general object of the invention to provide simple means for preventing the thread of a transferred bobbin from reentering the magazine and occupying a position in which it can interfere with the next bobbin to be transferred.

In weft replenishing looms more particularly of the multicolor type the magazine is provided with yielding supports or giveways on which a bobbin rests as it awaits transfer. At the time of transfer the bobbin is moved down from the magazine into the empty shuttle and the weft end of the bobbin, ordinarily held at its outer end to some form of thread holder, moves with the bobbin. Shortly after transfer the freshly replenished bobbin is picked and there is likelihood that the thread extending from the thread holder to the shuttle will be whipped back into the magazine and occupy a position where it can interfere with movement of the next bobbin to transfer position. It is an important object of the present invention to provide simple means, preferably in the form of bristles, on a bobbin support, so placed as to prevent reentry of the thread into the magazine.

The yielding bobbin tip supports are moved apart by the bobbin tip during a transfer operation and then return to their normal position prior to picking. It is a further object of the invention to mount the aforesaid bristles on one or both of the yielding supports so that the bristles will move away from thread restraining position during transfer to permit easy downward movement of the weft in the bobbin and then return to thread restraining position before the replenished shuttle is picked.

In some forms of thread control mechanism it is customary to employ a hook on the lay which moves the thread of the freshly transferred bobbin over a stationary hook on the loom frame. If the thread of the transferred bobbin is too high to be reached by the hook on the lay it will remain in the magazine or shuttle box and not be hooked over the stationary hook. When this happens the thread control mechanisms, such as those provided for removal of the thread after it is cut, are not likely to be able to act properly on the thread. It is a still further object of the invention to provide yielding means such as bristles which will keep the thread in a relatively low position after transfer so that it will be within the path of the hook on the lay.

With these and other objects in view which will appear as the description proceeds, the invention

2

resides in the combination and arrangement of parts hereinafter described and set forth.

In the accompanying drawings, wherein a convenient embodiment of the invention is set forth:

5 Fig. 1 is a side elevation of part of a weft replenishing mechanism having the invention applied thereto.

10 Fig. 2 is an enlarged view of the lower part of the magazine shown in Fig. 1.

15 Fig. 3 is an enlarged plan view of the bobbin tip supports and a bobbin tip thereon showing the relation of the weft end of the bobbin relatively to the bristles;

20 Fig. 4 is an enlarged vertical detailed section on line 4—4, Fig. 2, and

25 Fig. 5 is a diagrammatic view setting forth the operation of the invention.

Referring particularly to Fig. 1, the loom frame 10 supports a reserve bobbin magazine M, which in the present instance may be of the type which accommodates four stacks of reserve bobbins. The magazine has a transerrer arm 11 pivoted on a stud 12 held in fixed position on the stationary foot 13 of the magazine. The foot may be connected to the bobbin butt guiding and supporting inner plate 14 of the magazine and this plate by means of tie rods 15 supports the outer or bobbin tip guiding end plate 16 of the magazine.

30 Yielding supports are provided for both the butt and the tip of a bobbin in transfer position in the magazine, but since the invention is related more particularly to the thread extending from the bobbin tip the supports for the bobbin tip only are shown: Fig. 2 shows front and back 35 bobbin tip supports or giveways 17 and 18, respectively, which are mounted on links 19 and 20, respectively; Link 19 is pivoted on one of the tie rods 15 and is acted on by torsion spring 21 which tends to turn it in a counter-clockwise direction as viewed in Fig. 2, thereby exerting a force tending to move the front support 17 rearwardly, or to the right, Fig. 2. A stop screw 22 threaded into the link 19 engages a forwardly extending finger 23 of the support 17 to provide

40 vertical adjustment for the support 17. The support 17 by its engagement as at 24 with part of the magazine end plate 16 is limited as to its rearward and upward motion.

45 In similar manner the rear support 18 is acted upon by the torsion spring 25 on a rear tie rod 15 and acts to move the link 20 in a clockwise direction, thereby moving the back support 18 forwardly, or to the left as viewed in Fig. 2. Stop screw 26 similar to stop screw 22 and the rear support 18 is limited as to its forward and up-

50 ward motion.

ward movement by engagement with the end plate 16 as at 27. The adjacent ends of the supports 17 and 18 are spaced from each other and define between them a vertically extending thread passage 28, see Figs. 2 and 3.

The magazine has provision for storage of several stacks of bobbins and also has means for releasing the bobbins from their respective stacks so that they can move to a transfer position. The stacks of bobbins and releasing means are not shown in the drawings, but will be as usual. In Fig. 2 a bobbin T is shown in transfer position. When in this position the bobbin tip 30 will be supported by the front and back supports 17 and 18 and the weft end or thread W connected to the yarn on the bobbin will extend through or above the passage or thread slot 28. The weft thread W leads outwardly from the magazine to a thread holder designated generally at H, see Fig. 5.

The thread holder is preferably though not necessarily of the pneumatic type. It may be similar to thread holders used in a well-known type of two-color weft replenishing loom having a reciprocating pump which periodically creates subatmospheric pressures within the intake mouth 32 of the holder. The holder may, on the other hand, be made as shown in Patent No. 2,431,556 and be associated with a continuously running pump and controlled so that the intake mouth is open periodically. In either event the weft ends of the bobbins in the magazine and also the weft end of a bobbin T in the transfer position will lead to the thread holder and the latter will exert a slight tension on the thread.

The lay 35 of the loom is provided with a shuttle box 36 in which is located a shuttle S. The shuttle box includes in its construction a forwardly and upwardly extending hook 37, and a second hook 38 is secured in fixed position to some part of the loom.

Ordinarily there is no bobbin on the supports 17 and 18, but when a weft replenishing operation is to occur a bobbin moves in well-known manner to the transfer position with its tip resting on the tip of the supports 17 and 18, as shown in Figs. 2 and 3. As the lay beats up the trans-ferrer arm 11 descends and pushes the bobbin out of the magazine into the shuttle S, and in doing so effects a lowering of the thread or weft end W of the bobbin being transferred. During transfer the bobbin tip spreads the supports 17 and 18 apart, but they immediately return to the position shown in Fig. 2 before the replenished shuttle is picked.

The matter thus far described is of common construction and may be constructed as set forth for instance in Patent No. 1,030,748. The supports 17 and 18 are shown as one of several forms of bobbin tip supports, and the invention is not limited in its use to the precise form of supports shown herein.

In carrying the present invention into effect, a thread restraining means is provided which will prevent the thread of the transferred bobbin from returning upwardly through the passage 28 into the magazine. As shown herein this restraining means, designated generally at 40, takes the form of a plurality of flexible resilient bristles 41 which are mounted on the front bobbin tip support 17 and extend across the passage 28 as shown in the lower part of Fig. 2. The bristles may be held by a clip 42 fixed to the support 17 by a screw 43. The bristles are preferably on the outside of the magazine where they will be out

of the path of the bobbin tip 30 during bobbin transfer. The bristles are also preferably located between the thread holder and the thread passage or gap 28, although this relationship is not essential.

During a bobbin transferring operation the supports 17 and 18 will move apart so that passage 28 is widened temporarily and there will be a relative forward movement of the bristles with respect to the rear support 18. Because of this movement the bristles will not extend quite as far beyond support 18 as they normally do, and the thread W as it moves down with the bobbin will be able to bend the bristles downwardly and move from the dotted line position to the full line position shown in Fig. 5. Movement of the bristles by the thread will be due in part by the fact that the bristles are moved bodily in a direction away from their normal restraining position, and also in part due to the fact that the bristles are resilient and the thread is kept under tension by the holder H.

This action occurs at the time of bobbin transfer, and the supports 17 and 18 thereafter immediately return to their normal position, whereupon the bristles are restored to the position shown in Fig. 2 where they lie across the path of the weft thread W should the latter try to move back into the magazine by upward movement through the passage 28. As the shuttle is picked the thread W may be whipped upwardly, but the bristles will prevent it from entering passage 28. Also, the thread will extend from the bristles to the left, Fig. 5, and be in the path of hook 37 to be placed by it on hook 38 on the next lay beat-up, at which time the thread will become attached to the selvage of the cloth C.

From the foregoing it will be seen that the invention sets forth simple means which effectively prevents return of the weft of a transferred bobbin into the magazine. This means may take the form of flexible bristles mounted on one of the yielding or give-way supports for the bobbin tip and is preferably located between the thread passage 28 and the holder H, although this particular location is not essential in all forms of the invention. When the bristles are located as shown in Fig. 3, for instance, they are out of the path of the downwardly moving bobbin tip and will therefore not be damaged by it during transfer operation. The fact that the thread holder tensions the weft end assists the latter to deflect the bristles when the bobbin is transferred, especially in view of the fact that the bristles are close to the tip of the bobbin. The tendency of the thread to whip up through the passage 28 occurs when the shuttle is being picked and the bobbin tip has moved away from the bristles. The bend in the thread at this time produced by the underside of the bristles is much less than the bend produced by the top side of the bristles at transfer, and the bristles are better able to withstand the tension of the thread. Spreading of the supports 17 and 18 at bobbin transfer moves the bristles away from their normal restraining position and assists the thread to move to a position below the bristles. Also, the bristles are at such an elevation that without respect to the height of the thread holder the thread W of the incoming bobbin will not only be prevented from reentering the magazine, but will also be held within the range of motion of the movable hook 37.

Having thus described the invention it will be seen that changes and modifications of the fore-

going specific disclosure may be made without departing from the spirit and scope of the invention.

What is claimed as new is:

1. In a weft replenishing loom having a thread holder tensioning the weft end extending from the tip of a bobbin in a reserve bobbin magazine, bobbin tip support means on the magazine defining a thread passage through which said weft end passes downwardly when the bobbin is transferred, and flexible resilient means mounted on said bobbin support means extending across said passage yielding to permit downward movement of the weft end and effective to prevent upward movement of the weft into said passage subsequent to transfer of the bobbin.

2. In a weft replenishing loom having a reserve bobbin magazine and a thread holder tensioning the weft end of a bobbin in transfer position in a magazine, resiliently mounted bobbin tip support means defining a passage for the weft end normally in bobbin tip supporting position but moved by the bobbin tip when the bobbin is transferred, and flexible resilient means on said bobbin support means moved with respect to said passage when the support means is moved by the bobbin when the latter is being transferred to facilitate downward movement of the weft end, said flexible resilient means being normally positioned by the bobbin tip support means to limit upward movement of the weft end into said passage subsequent to bobbin transfer.

3. In a weft replenishing loom having a thread holder tensioning the weft end extending from the tip of a bobbin in a reserve bobbin magazine, bobbin tip support means on the magazine defining a thread passage through which said weft end passes downwardly when the bobbin is transferred, and flexible resilient means mounted on said bobbin support means between the thread holder and support means extending across said passage and yielding to permit downward movement of the weft end and effective to prevent upward movement of the weft

6
end into said passage subsequent to transfer of the bobbin.

4. In a weft replenishing loom having a thread holder tensioning the weft end extending from the tip of a bobbin in a reserve bobbin magazine, a pair of bobbin tip supports resiliently mounted on the magazine and normally in bobbin tip supporting position and defining between them a thread passage through which the weft end of the bobbin passes incident to transfer of the bobbin, and flexible bristles on one of said supports normally preventing the weft end from moving back into said passage subsequent to transfer of the bobbin.

5. In a weft replenishing loom having a reserve bobbin magazine, bobbin tip supports resiliently mounted and normally in position to support a bobbin tip, said supports being spaced to define a thread passage therebetween, bristles mounted on one of said supports out of the path of the bobbin tip when the latter is transferred, said one support when in normal position locating the bristles in the normal position thereof across said passage, said one support being moved by the bobbin tip incident to bobbin transfer and moving the bristles away from the normal position thereof to facilitate downward movement of the weft end in said passage, and said one support subsequent to transfer returning to normal position to return the bristles to the normal position thereof to prevent upward movement of the weft end of the transferred bobbin into said passage.

GEORGE N. PETERSON.
